UNITED STATES PATENT OFFICE

2,467,385

METHOD OF AND APPARATUS FOR LASTING
FOOTWEAR

Jacob S. Kamborian, West Newton, Mass.

Application December 16, 1944, Serial No. 568,471

35 Claims. (Cl. 12—1)

1

This invention pertains to the manufacture of footwear and relates more particularly to an improved method of and apparatus for use in lasting shoes, the present invention being a further development of the invention set forth in the United States patent to Kamborian No. 2,251,284 dated August 5, 1941.

That patent discloses the employment of means, for instance a pair of helically ribbed rolls, for gripping the lasting margin of the upper and exerting such stress as to draw the upper snugly about the last, while, at the same time, tending to move the lasting margin in a direction substantially parallel to the edge of the sole, in other words setting up a relative movement of the shoe and the rolls; in combination with wiping means, e. g. a rapidly vibrating reciprocating wiper, which urges the stressed lasting margin inwardly across the edge of the sole into contact with the bottom surface thereof to which it is secured by suitable means e. g. by adhesive applied prior or subsequent to the upper drawing operation or by metallic fasteners.

The present invention embodies means whereby the underlying principles of the above patent are attained. One object of this invention is the provision of means whereby the shoe being lasted is held with the bottom of the sole in a horizontal plane while the gripping rolls rotate upon axes at an angle of the order of ten to fifteen degrees to the vertical. Another object of this invention is to provide means which will act upon the lasting margin before it enters the bite of the gripping rolls and bring it into a plane substantially perpendicular to that of the shoe bottom. A further object of the invention is to provide an element positioned between the gripping means and the wiping means against which element the sole of the shoe being lasted is pressed by the operator, over which element the lasting margin is folded and by which element adhesive is introduced between the lasting margin and the sole so that the lasting margin will adhere to the sole when wiped into contact therewith, said adhesive being hot when introduced and having the property of setting quickly. A still further object of the invention is to provide as wiping means, two independently reciprocated blades so actuated and mounted that they move seriatim over the lasting margin and that one or the other at least of said blades is in contact with the lasting margin until the adhesive has set sufficiently to oppose any tendency thereof to separate from the sole, one or both of said blades being so mounted as to exert downwardly applied pressure upon the last-

2

ing margin. Other and further objects will appear from a consideration of the following detailed description of one embodiment of the invention and of the accompanying drawings wherein,

Fig. 1 is a plan view of the forepart of a shoe being lasted in accordance with the teachings of this invention, parts of the apparatus being in horizontal section;

Fig. 2 is a fragmentary elevation, showing the rolls by which the shoe upper is drawn closely about the last, the shoe being shown in transverse section and indicating the edge wall of the shoe and the plow by which the lasting margin is raised;

Fig. 3 is a fragmentary elevation looking in the direction of the arrow 3 in Fig. 1 illustrating the sequence of steps of the lasting operation and the relation of the lasting elements to the plane of the shoe, the latter being in vertical section;

Fig. 4 is a fragmentary elevation, partly in vertical section, illustrating the operation of the hold-down applicator;

Fig. 5 is a fragmentary side elevation, with parts in vertical section, illustrating one form of mechanism by which the lasting elements are supported and actuated; and

Fig. 6 is a plan and Fig. 7 a vertical section respectively of the wiping unit.

Figs. 1 to 4 inclusive of the drawings illustrate the lasting of a shoe of the type known in the trade as a "California," "force-lasted," or "slip-lasted" shoe. Such a shoe comprises an upper 10, a wrapper 11 secured to or constituting an extension of the upper to provide a lasting margin, a sock lining 12, the upper, wrapper and sock lining being jointed as by a line of stitches 13, and a platform 14 secured by adhesive or other suitable means to the sock lining. As shown at the right hand side of Fig. 1, the wrapper 11 is initially in a position extending substantially parallel to the upper 10. The assembled upper, wrapper and sock lining are pulled over a last 15 prior to the assembly of the platform there-

with. Since the wrapper lasting operation is to be performed with the shoe upside down, the wrapper may, for convenience, be described as initially depending, and corresponding language will be employed in the description of the wrapper lasting operation.

The various elements by which the wrapper lasting operation is to be performed are, in chronological order, a plow 20 by which the depending wrapper 11 is raised or up-lasted, a pair of rolls 30 by which the upper 10 is stressed snugly

about the last 15 and the platform 14, a nozzle-like device 40 by which the platform 14 is held down and through which adhesive is supplied, and impact-wiping means 50 by which the lasting margin is wiped in and hammered down upon and secured to the platform 14.

The plow 20 is reciprocated, as indicated by the double headed arrow 21 (Figs. 2 and 3) to engage and raise successive portions of the wrapper into the plane of the bite of the rolls 30. The rolls 30 are continuously driven in opposite directions as designated by the arrows 31, 32 in Fig. 1. Each roll is preferably provided with helically extended ribs 33 and the inner roll, i. e. the one over the platform is provided with a boss 34 against which the platform is held by the operator. (See Fig. 2.)

The device 40 will be designated a hold-down applicator because of the several functions thereof, as set forth above. The applicator 40 terminates in a toe 41, the base of which is, as shown in Fig. 4, substantially flat. During the lasting operation the shoe is held in position by pressing the platform against the boss 34 of the roll 30 and the base of the toe 41. The shoe is preferably positioned with the edge of the toe substantially at the edge of the platform and the upper surface of the toe is inclined upwardly from the edge so that as the lasting operation proceeds the margin is bent over and in contact therewith, whereby the wrapper is turned smoothly over the edge of the platform and adhesive may be applied thereto as will be hereafter described. When the platform 14 is made of fibre, rubber or similar material, the operator, by pressing the shoe upwardly, causes the hold down applicator to compress the edge of the platform so that the wrapper will be bent smoothly over the edge as indicated in Fig. 4. The applicator 40 is provided with a central adhesive transmitting conduit 42 which terminates in an outlet passage 43 at the base of the toe 41. A roller 44, in an outlet passage 45 in the upper surface, transfers adhesive from the conduit 42 to the inner face of the lasting margin as the latter moves therover.

The final step in the lasting operation is performed by the wiping means 50, here shown as two blades 51 and 52 which are independently reciprocated transversely over the lasting margin as indicated by the double headed arrows 53 and 54 on Fig. 1. The wiping means 50 are preferably so positioned that they act upon the lasting margin at an angle to the longitudinal axis of the shoe of the order of seventy-five to eighty degrees.

Various means for supporting and actuating the lasting elements may be provided. Fig. 5 illustrates one such means which follows in general the construction disclosed in the above mentioned United States patent. A machine frame 60 suitably supported upon a bench or table (not shown) is provided with a head 61 which extends forwardly of the front wall 62 of the frame. Mounted in bearings in said head is a horizontal shaft 63 continuously rotated by any suitable means (not shown) within a casing or chamber 64. The portion of the shaft within the chamber is provided with right and left hand worm threads 65 and 66 separated by a cam 67.

The plow 20 is integral with or mounted upon a rod 70 guided for vertical reciprocation within the head 61. The upper end of the rod 70 is yieldably held in contact with the cam 67 as by a spring 71 and the cam is so formed that the rod 70 and its plow 20 are given one or more

complete reciprocations for each rotation of the shaft 63.

The rolls 30 are rigidly secured to the lower ends of shafts 80 and 81 provided at their upper ends with worm wheels 82 and 83 which mesh with the threads 65 and 66 respectively. The shafts 80 and 81 are journaled in bearings so that they rotate freely. The shaft 81 is carried by a slide 84 so that, should occasion arise, it may be shifted forwardly from the shaft 80. This construction is similar to that set forth in the above patent.

The hold down applicator 40 is held in position by a clamp or strap 90 at one end of an arm 91 mounted upon a flange 92 on the head 61. Adhesive is supplied to the applicator from a tight tank or reservoir 93 suitably supported in the frame 60 and connected to the applicator by a tube 94. Mounted within the tank is a vertical pipe 95 the upper end of which terminates at the upper wall of the tank and the lower end of which projects below the bottom wall of the tank. Ports 96 in the pipe near the bottom of the tank admit adhesive into the pipe and port 97 connects the pipe to the tube 94. The lower end of the pipe 95 is closed by a removable plug 98 the upper surface of which is at the lower edge of the port 97. A plunger 99 normally positioned just above the ports 96 is carried at the lower end 30 of a rod 100 which extends through a bearing ring 101 beyond the top of the pipe. The plunger 99 may be depressed in any desired manner as for example by a lever 102 pivoted at one end upon a bracket 103 and connected at the other 35 end by a link 104 to a treadle (not shown). The rod 100 is connected to the lever 102 by a stud 105 which is received in a slot 106. Suitable means such as a spring 107 are provided to return the plunger to its normal position.

40 The space in the pipe between the ports 96 and 97 is preferably such that it will hold the amount of adhesive required to treat one shoe. Hence only a single complete depression of the plunger will be required during the lasting of each shoe.

45 The preferred adhesive is of the type that will set quickly when exposed to the air. Various types of such adhesive are known, most of which are thermoplastic. In order to maintain the adhesive in condition, the tank 93 is provided with 50 heating means 108, the tube 94 and the applicator are provided with an insulating jacket of any suitable type, a portion of which is indicated at J, and a supplementary heater 109 is provided at the toe 41. The temperature to 55 which the adhesive is raised may be varied according to the conditions present during the lasting e. g. material employed in the upper or platform under which the lasting takes place. Should it be found that the temperature of the adhesive is too high for the particular operation, a jet of cool air may be applied through a jet 110 (Fig. 1).

The blades 51 and 52 of the wiping means 50 are reciprocated by the rotation of a shaft 120 (Fig. 6) mounted in the frame 60. Fixed upon the shaft 120 are cams or eccentrics 121 and 122 enclosed by straps 123 and 124 upon rods 125 and 126 pivotally attached to the blades 51 and 52, the members 121 and 122 being so designed 70 and mounted as to cause the blades 51 and 52 to reciprocate in out of phase relationship. The outer ends of the rods 125 and 126 are supported by brackets 127 and 128 depending from plates 129 and 130 slidable in guides 131 and 132 fixed 75 to the under face of the flange 92. Rigidly sus-

pended from the head 61 are cam plates 133 and 134. Rolls 135 and 136 on the blades 51 and 52 are held yieldably in contact with the cams as by springs 137 and 138. Hence, as the blades 51 and 52 are advanced, the outer ends thereof are caused to press the lasting margin down firmly against the platform. It will be noted that the forward ends and the bottom forward edges of the blades are rounded to prevent any injury to the lasting margin. Since it is desired that the blades 51 and 52 act upon the lasting margin at an angle to the axis of the shoe, it will be understood that the shaft 120 is similarly positioned.

The operation of the lasting machine will now be described, it being understood that the shafts 63 and 120 are rotating and actuating the various elements as herein above described. The shoe (comprising an upper, a wrapper and a sock lining duly assembled and pulled over a last and having a platform adhesively secured to the sock lining) is presented by the operator to the machine with the wrapper depending. The shoe is held with the platform 14 firmly in contact with the boss 34 and the under face of the toe 41 so that the shoe bottom is substantially horizontal. (See Figs. 2 and 3.) A portion of the wrapper is engaged and raised or up-lasting by the plow 20 so that it will enter the bite of the rolls 30 whereupon the upper is drawn snugly around the last and against the edge wall of the platform and advanced as set forth in the above mentioned patent. The wiper blades 51 and 52 press the lasting margin down against the platform, the portion of margin between the rolls and wipers being bent over the upper face of the toe 41. Due to the composite motion of the blades, the lasting margin is both wiped and hammered down against the platform.

The operator, at the proper time, depresses the treadle and starts the flow of adhesive. The pressure exerted by the plunger 99 upon the adhesive in the line will break any film that might be formed in the mouth of the outlet passage 43, and the roller 44, being in contact with the lasting margin, is positively rotated thereby to insure delivery of adhesive to the lasting margin. As pointed out above a single depression of the plunger 99 will feed enough adhesive to insure the bonding of the lasting margin of each shoe. Should additional adhesive be required, the operator can depress the treadle a second time until the lasting of the shoe is completed. Alternative to the described arrangement, provision may be made for establishing fluid pressure within the tank 93 and the depression of the treadle caused merely to operate valve mechanism to control the outflow of adhesive, which flow will continue so long as the treadle is depressed.

While means are disclosed by which adhesive is applied both to the lasting margin and to the platform, it will be understood that under certain conditions adhesive need only be applied to one of such parts and that the hold down applicator will be modified accordingly, as by omitting the roller 44 and applying adhesive through the outlet passage 43 or by omitting the outlet passage 43 and applying adhesive by the roller 44.

Under certain conditions the wrapper may be unplastered by the operator before the shoe is presented to the machine. When this takes place the slide 84 may be actuated as set forth in the above patent to separate the rolls 30 so that the wrapper can be positioned therebetween, whereupon the slide is returned to its normal position

and the wrapper gripped between the rolls. The lasting operation is then completed as described above.

The essence of this invention resides in the provision and operation of the lasting elements 20, 30, 40 and 50 and while one means for supporting and operating such elements is shown in the drawings and described in detail it will be understood that other means for supporting and operating such elements may be employed without departing from the spirit and scope of the invention.

This invention has been shown in the drawings and described herein as employed in the manufacture of shoes of the "California" type. It will be understood however that it is not limited thereto and is applicable to the manufacture of other types of shoes. The claims are accordingly so drawn. The term "lasting margin" used therein covers not only the wrapper herein described which constitutes an extension of the upper, but also the margin of the upper itself in case no wrapper is provided and the term "sole" includes not only the platform herein disclosed but the insole, cushion or other intermediate sole.

I claim:

1. Shoe lasting apparatus comprising means for gripping the lasting margin of the upper and applying a lasting pull thereto, means for wiping and pressing said lasting margin against the sole of the shoe, and adhesive applying means including a toe having an upper surface and a base surface, means providing an adhesive transmitting conduit and adhesive outlet passages in said upper surface and in said base surface for applying adhesive directly to the inner face of the lasting margin and the sole prior to the operation of said wiping and pressing means whereby the lasting margin is bonded to the sole.

2. Shoe lasting apparatus comprising means for gripping the lasting margin of the upper and applying a positive lasting pull thereto, means for wiping and hammering said lasting margin against the sole of the shoe, and means for supplying adhesive prior to the operation of said wiping means whereby the lasting margin is bonded to the sole, said adhesive supplying means including an adhesive applying roll with which said lasting margin contacts.

3. Shoe lasting apparatus comprising means for gripping the lasting margin of the upper and applying a positive lasting pull thereto, means for wiping and hammering said lasting margin against the sole of the shoe, and means for supplying adhesive prior to the operation of said wiping means whereby the lasting margin is bonded to the sole, said adhesive supplying means including an adhesive applying roll with which said lasting margin contacts and having an outlet through which adhesive is fed to the sole.

4. Shoe lasting apparatus comprising means for gripping the lasting margin of the upper and applying a positive lasting pull thereto, means for wiping and pressing said lasting margin against the sole of the shoe, and means for supplying adhesive prior to the operation of said wiping means whereby the lasting margin is bonded to the sole, said adhesive supplying means comprising a foot which holds the sole down against the pull applied by the gripping means, said foot being provided with adhesive delivery orifices operative to deliver adhesive to the sole and to the inner surface of the lasting margin, respectively.

5. In an apparatus for lasting shoes including

means for gripping the lasting margin of the upper and applying a lasting pull thereto, and means for wiping said lasting margin against the sole of the shoe, means interposed between said gripping means and said wiping means for holding the sole of the shoe down against such lasting pull, which means comprises a toe having an adhesive transmitting conduit, an inclined surface over which the lasting margin is bent and a substantially flat base and an outlet passage in said base by which the adhesive in the conduit is supplied to the sole.

6. In an apparatus for lasting shoes including means for gripping the lasting margin of the upper and applying a positive lasting pull thereto, and means for wiping said lasting margin against the sole of the shoe, means interposed between said gripping means and said wiping means for holding the sole of the shoe down against such lasting pull, which means comprises a toe having an adhesive transmitting conduit, an inclined surface over which the lasting margin is bent and a substantially flat base and an outlet passage in the surface over which the lasting margin is bent by which passage the adhesive in the conduit is supplied to the lasting margin.

7. In an apparatus for lasting shoes including means for gripping the lasting margin of the upper and applying a positive lasting pull thereto, and means for wiping said lasting margin against the sole of the shoe, means interposed between said gripping means and said wiping means for holding the sole of the shoe down against such lasting pull, which means comprises a toe having an adhesive transmitting conduit, an inclined surface over which the lasting margin is bent and a substantially flat base and having an outlet passage in the inclined surface over which the lasting margin is bent by which passage the adhesive in the conduit is supplied to the lasting margin, said passage containing a roll which bears against the lasting margin.

8. Shoe lasting apparatus comprising means for up-lasting the lasting margin of the upper, means for wiping said margin against the sole of the shoe, said wiping means comprising a plurality of independently reciprocable wiping elements, means for reciprocating said elements in out of phase relationship, and means for supplying adhesive to the lasting margin before said wiping elements operatively engage said margin.

9. Shoe lasting apparatus comprising means for up-lasting the lasting margin of the upper, upper stretching and feeding means constructed and arranged to grip the margin of the upper while lasting stress is imparted to said margin in a direction away from the bottom of the last and to exert work feeding stress in a direction substantially parallel to the edge of the insole, means for engaging the sole and holding it down against such lasting pull and tending to bend said lasting margin over said hold-down means while applying adhesive to the lasting areas, and means for wiping said lasting margin against the sole of the shoe, said sole engaging means including a toe having an adhesive transmitting conduit and an outlet passage therefrom whereby adhesive is applied upon the sole of the shoe.

10. Shoe lasting apparatus comprising means for up-lasting the lasting margin of the upper, means for gripping the up-lasting lasting margin and applying a positive lasting pull thereto, means for engaging the sole and holding it down against such lasting pull and for applying adhesive to the lasting areas, and means tending to bend said lasting margin over said hold-down means

while wiping said lasting margin against the sole of the shoe, said sole engaging means including a toe having an adhesive transmitting conduit and a roller supplied with adhesive from the conduit which roller applies adhesive upon the inner face of the lasting margin as it is bent over said engaging means.

11. Shoe lasting apparatus comprising means for up-lasting the lasting margin of the upper, means for gripping the up-lasting lasting margin and applying a positive lasting pull thereto, means for engaging the sole and holding it down against such lasting pull and for applying adhesive to the lasting areas, and means tending to bend said lasting margin over said hold-down means while wiping said lasting margin against the sole of the shoe, said sole engaging means including a toe having an adhesive transmitting conduit and a roller supplied with adhesive from the conduit, which roller applies adhesive upon the inner face of the margin as it is bent over said engaging means and an outlet passage from the conduit by which adhesive is applied upon the sole of the shoe.

12. In an apparatus for lasting shoes including means for gripping the lasting margin of the upper and for applying a lasting pull thereto and means for wiping said lasting margin against the sole of the shoe, hold-down means, interposed between said gripping means and said wiping means, for holding the sole of the shoe down against such lasting pull and for applying adhesive to bond the lasting margin to the sole, said means including a toe having an adhesive transmitting conduit and outlet passages opening at its upper surface and at its bottom surface respectively by which the adhesive in the conduit is applied to the lasting areas of the shoe, a reservoir for the adhesive, a tube by which the adhesive is carried from said reservoir to said hold-down means, and means for heating the adhesive so that the adhesive applied to the shoe is at a desired temperature.

13. In an apparatus for lasting shoes, means for applying adhesive to the sole and lasting margin of the upper, said means comprising a toe having an adhesive transmitting conduit and outlet passages through which the adhesive is applied in liquid form directly to the sole and to the lasting margin of the shoe, a reservoir for the adhesive, a tube by which the adhesive is carried to said conduit, and means for heating the adhesive.

14. In an apparatus for lasting shoes, means for applying adhesive comprising a toe having an adhesive transmitting conduit and outlet passages through which the adhesive is applied in liquid form directly to the sole and to the lasting margin of the shoe, a reservoir for the adhesive, a tube by which the adhesive is carried to said conduit, means for heating the adhesive in the reservoir, a jacket enclosing the tube, and means for heating the adhesive in the toe.

15. In an apparatus for lasting shoes, means for applying adhesive to the shoe being lasted comprising a toe having an adhesive transmitting conduit, an outlet passage leading from the conduit to the outer surface of the toe, and a roller mounted in said passage whereby adhesive is transferred from the conduit and applied to the shoe being lasted.

16. In an apparatus for lasting shoes, means for applying adhesive to the shoe being lasted comprising a toe having an adhesive transmitting conduit, two outlet passages leading from the conduit to the outer surface of the toe, and

a roller mounted in one of said passages, whereby adhesive is transferred from the conduit and applied to the shoe being lasted by the roller in one passage, and directly by the other passage.

17. In an apparatus for lasting shoes, means for wiping the lasting margin against the sole of the shoe which comprises a pair of reciprocating blades, each blade having an independent travel, and means for reciprocating said blades, the travel of the blades being such that each blade is at all times during the lasting operation in contact with the lasting margin.

18. In an apparatus for lasting shoes, means for wiping the lasting margin against the sole of the shoe, the shoe being movable relative to the wiping means, which means comprises a pair of reciprocating blades, each blade having an independent travel, and means for reciprocating said blades, the travel of the blades being such that each blade is at all times during its forward reciprocation in contact with the lasting margin and at least one of such blades is in contact with the lasting margin during the lasting operation.

19. In an apparatus for lasting shoes, means for wiping and pressing the lasting margin of the upper against the sole of the shoe, the shoe being movable relative to the wiping and pressing means, said means comprising a pair of independently movable blades, reciprocable transversely of the lasting margin, at least one of said blades being at all times in contact with the lasting margin, and means for reciprocating said blades.

20. In an apparatus for lasting shoes, means for wiping and pressing the lasting margin of the upper against the sole of the shoe, the shoe being movable relative to the wiping and pressing means, said means comprising a pair of movable blades, independently reciprocable transversely of the lasting margin, at an acute angle to the longitudinal axis of the shoe, and means for reciprocating said blades.

21. In an apparatus for lasting shoes, means for wiping the lasting margin of the upper against the sole of the shoe, the shoe being movable relative to the wiping means, said means comprising a pair of movable blades, independently reciprocable transversely of the lasting margin, at an angle to the longitudinal axis of the shoe of the order of 75 to 80 degrees, and means for reciprocating said blades.

22. In an apparatus for lasting shoes, means, including a rotating roll, for applying a lasting pull to the lasting margin of the upper, means for supplying hot adhesive to such lasting margin, and means for wiping the lasting margin onto the sole, such wiping means remaining in contact with the margin until the adhesive thereon has set sufficiently to oppose any tendency thereof to separate from the sole.

23. In an apparatus for lasting shoes, means, including opposed parts between which the lasting margin is gripped, one at least of said parts being a rotating roll, for applying a lasting pull to the lasting margin of the upper, means for supplying hot adhesive to such lasting margin, and means for wiping the lasting margin onto the sole, such wiping means being movable over the lasting margin and remaining in contact therewith until the adhesive thereon has set sufficiently to oppose any tendency thereof to separate from the sole.

24. In an apparatus for lasting shoes, means, including a pair of rotating rolls between which the lasting margin is gripped, for applying

a lasting pull to the lasting margin of the upper, means for supplying hot adhesive to such lasting margin, and means for wiping the lasting margin onto the sole, such wiping means including a pair of alternately acting wipers reciprocable over said lasting margin and contacting the wiped-in margin until the adhesive thereon has set sufficiently to oppose any tendency thereof to separate from the sole.

10 25. In an apparatus for lasting shoes, means for applying a lasting pull to the lasting margin of the upper, means for supplying hot adhesive to such lasting margin, and means for wiping the lasting margin onto the sole, such wiping

15 means comprising a pair of independently reciprocable blades, and means for reciprocating said blades in out of phase relationship transversely of the lasting margin at an angle toward said adhesive supplying means.

20 26. That method of lasting a shoe of the kind which includes an upper provided with a down-turned lasting margin, a sock lining, and a mid-sole, which comprises the steps of progressively advancing the shoe while turning the lasting margin of the upper so that it projects upwardly beyond the bottom surface of the sole, gripping said turned margin and pulling the upper snugly about the edge wall of the sole while exerting a feeding action on the shoe, and wiping said lasting margin onto the sole as the shoe is fed.

27. That method of lasting a shoe of the kind which includes an upper provided with a down-turned lasting margin, a sock lining, and a mid-sole, which comprises the steps of progressively advancing the shoe while turning the lasting margin of the upper so that it projects upwardly beyond the bottom surface of the sole, gripping said turned margin and pulling the upper snugly about the edge wall of the sole and while exerting a feeding action on the shoe, and wiping said lasting margin onto the sole as the shoe is fed, said wiping step being performed in two independent successive operations.

28. That method of lasting a shoe of the kind which includes an upper provided with a down-turned lasting margin, a sock lining, and a mid-sole, which comprises the steps of progressively advancing the shoe while turning the lasting margin of the upper so that it projects upwardly beyond the bottom surface of the sole, gripping said turned margin and pulling the upper snugly about the last and against the edge wall of the sole while exerting a feeding action on the shoe, and wiping said lasting margin onto the sole as the shoe is fed, said wiping step comprising two

50 independent successive operations each of which stresses the lasting margin around the edge wall of the sole, one at least of said steps also including yieldably pressing the lasting margin against the sole.

55 29. That method of lasting a shoe of the kind which includes an upper provided with a down-turned lasting margin, a sock lining, and a mid-sole, which comprises the steps of progressively advancing the shoe while turning the lasting margin of the upper so that it projects upwardly beyond the bottom surface of the sole, introducing adhesive between the lasting margin and the sole, and thereafter wiping said upturned lasting margin onto the exposed surface of the sole.

70 30. In a lasting machine for lasting-in the platform covers of platform shoes, platform cover turning means to which a shoe may be fed so as to cause the platform cover to be turned progressively, a device adjacent to said turning means

11

for applying cement in preparation for the adhesive-laying of the turned cover, means for gaging the shoe in relation to the turning means and to the cement-delivering device, and means for wiping-in the cover.

31. In a machine of the class described having means for applying adhesive to the inner surface of the wrapper of a force lasted shoe, reciprocating wrapper-turning means which moves in a direction which is heightwise of the shoe and which is arranged to engage the wrapper as the latter approaches the adhesive-applying means, said wrapper-turning means being operative progressively to turn the wrapper right side out, means for actuating the wrapper-turning means, a cement-delivery device operative to apply adhesive to the inner surface of the wrapper, and a reciprocating wiper for wiping-in the wrapper.

32. In a lasting machine for lasting-in the platform covers of platform shoes, a cover-turning tool adapted to enter between an upturned portion of the platform cover and the body of the shoe and at least partially to turn the platform cover, means for moving said tool back and forth to increase its turning effect upon the platform cover, cover-tensioning means comprising opposed elements between which the cover is gripped after it is turned by said turning tool, said tensioning means being constructed and arranged to stress the cover heightwise of the shoe, and wiper means operative to wipe-in the tensioned cover.

33. Apparatus for progressively turning, cement-coating and wiping-in the wrapper of a California shoe, said apparatus comprising means for gripping and stressing the wrapper heightwise of the shoe, means operative to turn the wrapper into a position such that it may readily be seized by the gripping means as it approaches the latter, means operative to apply adhesive to the inner surface of the wrapper, and wiping means for wiping-in the wrapper.

34. Apparatus for progressively turning, cement-coating and wiping-in the wrapper of a California shoe, said apparatus comprising opposed relatively movable gripper elements operative to grip the wrapper between them while stress is being applied to the wrapper in a direction heightwise of the shoe, a plow reciprocable in a path substantially perpendicular to the shoe bottom and which is operative to engage that

12

part of the wrapper which has not yet been seized by the gripper elements and to turn the wrapper thereby to present it in position for seizure by the gripper elements, means operative to apply adhesive to the inner surface of the wrapper, and wiping means for wiping-in the wrapper.

35. In a machine wherein a California-type shoe is fed to bring the platform cover of the shoe progressively into operating relation to cover-turning means, said machine comprising a reciprocating cover-turning plow movable heightwise of the shoe, a part which contacts the exposed surface of the shoe bottom thereby to oppose movement of the shoe as a whole with the plow, relatively movable gripper elements operative to seize between them the cover as it is turned by the plow, said gripper elements being arranged to hold that part of the cover which is held between the gripper elements substantially perpendicular to the shoe bottom, means for applying adhesive to the inner surface of the platform cover after it has been seized by the gripper elements, and wiping means for wiping-in the cover.
